UNITED STATES PATENT OFFICE.

EDWARD G. GERMER AND EDWARD GERMER, JR., OF ERIE, PENNSYLVANIA.

GAS BURNER.

Application filed December 24, 1921. Serial No. 524,582.

To all whom it may concern:

Be it known that we, EDWARD G. GERMER and EDWARD GERMER, Jr., citizens of the United States, residing at Erie, in the county 5 of Erie and State of Pennsylvania, have invented new and useful Improvements in Gas Burners, of which the following is a specification.

The gas burner of this invention is especially designed for cooking stoves, hot plates and the like where it is desired to radiate heat upwardly. Stoves have been developed in which hollow radiants have been used but such radiants have been so arranged 10 as to radiate the heat in a general horizontal direction as is common with heating stoves as distinguished from an upward direction as is common with cooking stoves. With the present invention the radiants radiate the 15 heat upwardly.

The invention is illustrated in the accompanying drawings as follows:—

Fig. 1 shows a central section through the burner on the line 1—1 in Figs. 4 and 5.

Fig. 2 a plan view of a radiant.

Fig. 3 a side view of a radiant.

Fig. 4 a plan view of the burner assembled.

Fig. 5 a plan view of the burner with the 20 radiants and retainer removed.

Fig. 6 a section on the line 6—6 in Fig. 1 showing the construction of the burner jets.

1 marks the burner chamber leading from the usual mixer (not shown), 2 the tips or caps for the burner jets forming chambers 25 3 extending upwardly from the burner chamber, the caps or tips having the top walls 4 through which the vertical slits 6 extend. These slits extend downwardly at 7 40 into the side walls of the caps thus forming lateral openings as well as upwardly extending openings through the slits. The character of the flame may be controlled by varying the relative thickness of the side 45 and top walls. In the present construction the top wall is made thicker than the side walls and consequently there is a slightly greater relative resistance through the slits upwardly than at the side by reason of which 50 the flame is spread or given a fan-shape. The caps or tips 2 are arranged in a cluster on the top of the burner, there being a plurality of these caps so that the slits may be in alinement. This simplifies the manufacture 55 in that they may be cut with the same operation of the machine.

8 marks the retainer which as shown is formed in one piece forming a cluster of retainers for the different burner jets. These rest on the notched projections 9 and the 60 notches 10 on the face of the burner. The retainers have the openings 11 for introducing air for combustion through the walls of the retainer.

The retainers have the annular shoulders 65 12 on which are placed the radiants 13. The radiants are preferably in the form of annular rings which have the inwardly extending projections 14 in the path of the flame. The rings have the projections 15 on one 70 face and detents 16 on the opposite face by means of which the radiants are kept in register and the detents and projections are arranged to bring the projections of one ring in staggered relation to the projections 75 of the next ring. Preferably a plurality of these radiant rings are placed in the retainer and a spider-shaped grid 17 is arranged over the top of the ring-shaped radiants, the grid being of radiant material and 80 having projections 18 corresponding to the projections 15 and so placed as to bring the arms of the grid in staggered relation with the projections 14. 19 represents a stove top.

In the operation the flame from the jets is carried through the radiants and they are heated to a glow which radiates upwardly, thus assuring a more perfect combustion of the gases and at the same time the added 90 radiant heat effect.

What we claim as new is:—

1. In a burner, the combination of a burner jet; and a series of superimposed radiants above the jet, said radiants being 95 larger horizontally than vertically and formed to seat with uniformity one upon another.

2. In a burner, the combination of a burner jet; and a series of superimposed radiants above the jet, said radiants being larger horizontally than vertically and formed to seat with uniformity one upon another and adapted to radiate upwardly.

3. In a burner, the combination of a 100 burner jet; and a radiant above the jet, said radiant being formed with an annular rib and inwardly extending projections in the path of the flame.

4. In a burner, the combination of a 110 burner jet; and a series of superimposed radiants above the jet, said radiants being

formed with annular rings and inwardly extending projections and having interlocking protuberances and indentures placed to stagger the projections.

5. In a burner, the combination of a burner jet; a series of superimposed radiants above the jet, said radiants being larger horizontally than vertically and formed to seat with uniformity one upon 10 another; and an enclosing retaining wall for the radiants.

6. In a burner, the combination of a burner jet; a radiant having an annular surrounding rib with inwardly extending portions, said radiant being larger horizontally than vertically and subjected to the direct action of the flame to produce incandescence above the jet; and a grid superimposed on the radiant.

20 7. In a burner, the combination of a burner jet; a radiant formed with an annular ring with inwardly extending projections; and a grid above the radiant having arms staggered with relation to the projections.

8. In a burner, the combination of a jet; an annular radiant above the jet; a grid of radiant material on the radiant; and a retainer around the radiant and grid, said radiant and grid being adapted to radiate upwardly.

9. In a burner, the combination of a jet; a radiant above the jet; a grid on the radiant; inwardly extending projections on 35 the radiant; and interlocking protuberances

and indentures on the grid and radiant positioning the grid with relation to the radiant to stagger the grid relatively to the projections.

10. A radiant for stoves having an annular ring and inwardly extending projections and having protuberances and indentures thereon adapted to interlock with an adjacent radiant.

11. In a burner, the combination of a burner chamber; an upwardly extending cap; slits extending through the top wall of the cap below the lower surface of said top wall into the side walls of the cap forming lateral jet exits for the cap; and an annular radiant above the cap adapted to radiate upwardly.

12. A burner having a burner chamber; and a series of caps grouped around a center on the chamber, said caps having slits therethrough, the slits on a plurality of caps being in parallel.

13. In a burner, the combination of a burner chamber; an upwardly extending cap on the chamber; and slits extending downwardly into the cap below the undersurface of the top wall of the cap forming lateral jet exits from the cap, the top wall being thicker than the side wall to spread the flame.

In testimony whereof we have hereunto set our hands.

EDWARD G. GERMER,
EDWARD GERMER, JR.
